UNITED STATES PATENT OFFICE

MAXIMILIAN MATHIAS, OF BERLIN, GERMANY, ASSIGNOR TO SIEMENS & HALSKE AKTIENGESELLSCHAFT, OF SIEMENSSTADT, NEAR BERLIN, GERMANY

AUTOMATIC TELEPHONE SYSTEM

Application filed November 17, 1930, Serial No. 496,303, and in Germany December 12, 1929.

The invention relates to a circuit arrangement for telephone systems with automatic operation.

In such systems experience has shown that for each group of subscribers' lines a definite number of connectors is necessary dependent upon the number of simultaneous connections set up during the busy hour. During the greater part of the day, however, some of these connectors are very little used since the busy hour occurs only at particular times of the day. The greatest density of traffic, however, occurs at different groups at different times.

15 The object of the present invention is to reduce the number of connectors which are necessary for dealing with the peak load but which are not used in ordinary operation and are, therefore, uneconomically employed.

20 This is effected in that a portion of the connectors of the group are accessible in known manner over individual trunk lines from the switches of the preceding switching stage, while each of the remaining connectors of

25 the group is connected with a connector of another group to a common trunk line which is connected with various outlets from the preceding switching stage. This permits each connector which is not used during a

30 portion of the day to be arranged in such a manner that certain of the control devices are provided in common, therefore, an appreciable saving in switching devices is effected without any reduction in the number of connectors which are necessary for dealing with the peak load in each group.

The two figures show one embodiment of the invention, and Fig. 1 indicates the connection of the trunk lines VL between group 40 selectors GW and connectors LW; I, II, and III indicate three hundred groups of connectors. For each of these groups only four connectors are shown. The first two connectors of each group are connected in known manner with the trunk lines VL1, VL2, VL3, VL4, VL7, VL8 from the appropriate level of the preceding group selectors. The last but one connectors of the three hundred groups are connected together and extend 45 over the common trunk line VL5 to the last

but one contact of each level of the group selectors while the last connector of the individual hundred groups are connected in common over the trunk line VL6 with the last contact of each level of the individual 55 group selectors.

Fig. 2 shows the circuit arrangement of three such common connectors W1, W2, W3, which are accessible over the common trunk line VL_a, VL_b, by way of the three means 60 of access Z1, Z2, Z3 from the preceding group selectors.

The arrangement operates in the following manner: Suppose e. g. that switch W2 is seized by way of access Z2 from the preceding group selector, relay C2 operates from earth, battery, contact 1_b, off-normal contact 2_{k2}, winding 1 of relay C2, *c*-lead, earth, preceding group selector which is not shown. Relay C2 operates its contact 3_{c2} to the position 4_{c2}, thereby completing a locking circuit for itself. Moreover, it operates contact 5_{c2} to position 6_{c2} and contact 7_{c2} to position 8_{c2} and closes contact 9_{c2}. Relay B thereupon operates from earth, contact 70 9_{c2}, relay B, battery, earth. Relay B thereupon opens contact 1_b and closes contact 10_b. The opening of contact 1_b prevents relays C1 and C3 being energized as long as switch W2 is in use, and thus prevents 80 switches W1 and W3 being seized at the same time.

If now interrupted earth is connected to the *a*-lead in the group selector in order to operate the connector W2, relay A is operated 85 a corresponding number of times. On each energization it operates contact 39_a to position 11_a and thereby closes a circuit for the vertical magnet H2 from earth, contacts 11_a, winding 1 of relay V, 12_u, 13_{c3}, 8_{c2}, 14_{u2}, vertical magnet H2, battery, earth, so that the wipers of the switch W2 are raised in this manner to the desired level. On the first vertical step the off-normal contacts 15_{k2} are closed so that relay M2 operates from earth, contact 15_{k2}, relay M2, battery, earth, and closes contact 16_{m2} and operates contact 17_{m2} to the position 18_{m2}. Simultaneously with the first energization 95 of the vertical magnet H2 relay V is en- 100

ergized in the same circuit over its winding 1 and holds up throughout the train of impulses owing to the intermittent short-circuiting of its winding II. Accordingly, contact 19v is held open throughout the series of impulses so that no circuit is completed for relay U over its winding I and it cannot complete the circuit of the rotary magnet D2 by operating contact 12u to the position 21u.

At the end of the train of impulses relay V deenergizes and brings up relay U from earth, contacts 16m2, 19v, 20c3, 6c2, winding I of relay U, contacts 13c3, 8c2, 14w2, vertical magnet H2, battery, earth. Relay U operates its contact 12u to position 21u, opens its contact 33u and closes its contact 23u.

When the next series of impulses arrives over the a-lead, relay A again operates correspondingly, and each time closes a circuit for the magnet D2 from earth, contact 11a, winding I of relay V, 21u, 22p, 18m2, rotary magnet D2, battery, earth. During this series of impulses relay V again energizes so that relay U is held energized over its second winding in the circuit, earth, contacts 10b, 23u, 28v, winding II of relay U, battery, earth, and thereupon maintains contact 29u in the position 30u.

After switch W2 has been set in this manner by the last train of impulses on to the desired subscriber's line, if this line is idle relay P operates from earth, contacts 10b, 23u, 24v, windings II and I of relay P, c-wiper of the switch W2, to battery in the preselector (not shown) of the wanted subscriber's line. Upon the operation of relay P, contacts 25p, 26p and 27p are closed so that the seized subscriber's line is guarded against further seizure by the short-circuiting of winding II of relay P and the line VL_a, BL_b is switched through to the subscriber's line. Relay P, moreover, on operating operates contact 22p to the position 23p so that in consequence of the slow release of relay U, relay V is energized over its third winding in the circuit, earth, slow interrupter LU, contact 30u, winding III of relay V, contacts 31y, 23p, 18m2, magnet D2, battery, earth. Relay V closes its contact 32v, and thereby connects ringing current from the ringing lines RM to the outgoing a-lead. On the release of relay U contact 30u is returned to position 29u so that thereafter relay V is only energized every five seconds and, therefore, transmits ringing current to the wanted subscriber for these intervals.

When the subscriber replies, relay Y operates from earth, relay Y, contact 27p, b-wiper of the switch W2, subscriber's loop, a-wiper of the switch W2, contact 26p, relay A, battery, earth. Relay Y opens its contact 31y and thereby stops the transmission of ringing current.

If the wanted party is busy, relay P does not operate and the calling party receives

busy tone in the usual manner, which is not shown.

Instead of setting up a connection in this manner by the setting of only a particular connector, the connection may be set up in such a manner that all the connectors associated with the common trunk line are operated on to the same line by the incoming series of impulses, while the connection to the desired line is effected by switching means associated with each connector which become operative on the seizure of a particular access to the trunk line. On the termination of the conversation the release of the connection is effected by the calling party, and by opening the c-lead in the preceding group selector relay C2 is deenergized so that relay B deenergizes also and relay P is deenergized in turn by the opening of its circuit at contact 10b. The operation of contact 23p to the position 22p thereby produced closes a circuit for the rotary magnet D2 from earth, battery, magnet D2, contacts 18m2, 22p, 33u, 34c1, 5c2, 20c3, 19v, 16m2, earth.

Magnet D2 thereupon advances the wipers of the switch one step and at the same time short-circuits itself at its interrupter contacts 35d2. Magnet D2 thereupon releases so that its energizing circuit again becomes operative, and by this second energization the wipers of the switch are advanced a further step. Contact 35d2 is then again closed so that the magnet again releases and the cycle continues until the switch W2 reaches its normal position. When this occurs contact 2k2 is again closed and 15k2 opens so that the circuit for relay M2 is interrupted and contact 16m2 is opened and 18m2 is returned to position 17m2. All the apparatus is then restored to normal.

What is claimed is:

1. In an automatic telephone system, a selector having a plurality of groups of bank contacts, a plurality of groups of connectors, individual trunk lines extending from the first group of selector bank contacts and terminating in connectors in the first group of connectors, other individual trunk lines extending from another group of said selector bank contacts and terminating in another group of connectors, and other trunk lines multiplied to both groups of said selector bank contacts and common to a connector in each of said connector groups.

2. In an automatic telephone system, a plurality of groups of connectors, individual trunk lines over which certain of the connectors in each of the groups are accessible to the preceding switches, and a common trunk line over which the remaining connector in each group is accessible to said preceding switches.

3. In an automatic telephone system, a plurality of groups of connectors, individual trunk lines over which certain of the connectors in each of the groups are accessible to

the preceding switches, a common trunk line over which the remaining connector in each group is accessible to the preceding switches, and switching means common to all the connectors connected to the common trunk line for effecting the necessary operations for completing a connection.

4. In an automatic telephone system, a plurality of groups of connectors, individual trunk lines over which certain of the connectors in each of the groups are accessible to the preceding switches, a common trunk line over which the remaining connector in each group is accessible to said preceding switches, a test conductor individual to each connector connected to the common trunk line, and means associated with said test conductor for preparing for operation the connector individual to said test conductor.

10 5. In an automatic telephone system, a plurality of groups of connectors, individual trunk lines over which certain of the connectors in each of the groups are accessible to the preceding switches, a common trunk line over which the remaining connector in each group is accessible to the preceding switches, means associated with the common trunk line for receiving incoming impulses, a test relay associated with each connector connected to the common trunk line, means effective upon the operation of a test relay for preparing for operation the setting circuit of the associated connector, and means operative under control of the impulse 25 receiving means for positioning said connector.

20 6. In a telephone system, a plurality of groups of lines, a like plurality of groups of connectors, individual trunk lines over which certain of the connectors in each of the groups are accessible to the preceding switches to establish connections to subscribers in any of said groups of lines, and a common trunk line over which the remaining connector in each of said groups is accessible to said preceding switches to establish connections to subscribers in any of said groups of lines.

25 7. In a telephone system, a connector comprising only operating magnets and a set of wipers for completing connections to subscribers in one hundred group of lines, a like connector for completing connections to subscribers in a different hundred group of lines, a common trunk line over which said connectors are accessible to preceding switches, a test conductor individual to each of said connectors for preparing for operation the 30 connector individual thereto, a controlling relay apparatus adapted to be temporarily associated with either of said connectors, and means including said controlling relays operated responsive to the seizure of one of 35 said connectors for disabling the test con-

ductor individual to the other of said connectors.

In witness whereof, I hereunto subscribe my name this 21st day of October, A. D. 1930.
